CAR CONSTRUCTION

Minot C. Blest and George A. Suckfield, Avalon, Pa., assignors, by direct and mesne assignments, of one-half to Pressed Steel Car Company, Pittsburgh, Pa., a corporation of New Jersey, and one-half to The Youngstown Steel Door Company, Cleveland, Ohio, a corporation of Ohio

Application November 5, 1932, Serial No. 641,380

11 Claims. (Cl. 105—409)

The invention pertains to repair construction for wooden box cars and has for its object the provision of a car side replacement which can be mounted upon the car and utilize the original

5 roof and underframe.

Prior to a period of from 10 to 15 years ago a great many of the box cars were built with wood side construction combined with steel roof and underframe. These wood sides in recent years 10 have been displaced by steel when building new cars, because of greater strength in the body and also requiring less expenditure of time and money for maintenance. Many older cars, however, are still serviceable and repairs thereto are usually in 15 replacing rotted or damaged members of the wood sides. Many of these old wood cars are either in need or will soon be in need of major repairs.

These older cars have steel underframes and roof which are still serviceable and in many cases 20 require no replacements. Most of the ends of such cars were of steel and therefore still serviceable. To replace the wood sides with new wooden members requires dismantling the superstructure of the car and a complete rebuilding of same. Although 25 the old roofs and ends are utilized, much labor is spent in removing them and reassembling. The result of such work is a car that will have additional years of revenue earning service.

In our invention it is proposed to replace the 30 old wood side members with a steel side construction which can be assembled with the existing roof, underframe and ends so as to produce a steel sheathed car of greater strength than the original wood car and one which requires less 35 maintenance.

The invention also contemplates assembling these repair constructions in one piece before 40 erecting same upon the car. In cases where sufficient shop equipment is not available to handle such a large construction as a unit, the side can be spliced at the side door openings. In some cases, it may be necessary to assemble the individual pieces of the side upon the car, but the preferred method is to assemble the entire side 45 separate from the car and erect it upon the car in one or two pieces. In this manner, the old wood side construction may be removed with a minimum of disturbance to the other parts of the car, thus reducing the cost of the repairs.

50 By reason of its construction, as will be later explained in detail, the repaired side is constituted as a girder solidly tying together the superstructure of the car to its underframe. The resultant advantages of strength, resistance to destructive weaving and loosening of the individual

members of the side, and added resistance to deterioration of steel over wood is soon apparent in the cost of maintenance.

Referring now to the drawings, Fig. 1 shows in elevation our proposed repair construction; Figs. 2 and 3 are sections along the lines 2—2 and 3—3 of Fig. 1; Figs. 4 and 5 are vertical sections through Fig. 1 and show modifications in the manner of securing the repair construction to the car in cases where different underframe 10 and roof conditions exist. This repair construction comprises a top member or side plate 2, bottom member 3, side posts 4 and steel sheathing 5.

Reference character 1 indicates a partial outline of the car to be repaired, on which the top member or side plate 2 partly replaces the old wood side plate. In cases where the construction is assembled as a unit the member 2 extends the full length of the side and is connected to one end of each of the existing metallic ends. The member 2 in the preferred form comprises a rolled structural member of Z-shape with the web horizontal, the inner flange directed upwardly and the outer flange downwardly. It is to this inner upwardly directed flange 6 the ends of the carlines 20 are connected. In order that a rigid connection may be secured and to reduce weaving of the superstructure a gusset plate 7 is secured to the roof carlines for attachment to the flange 6 of the member 2. This gusset 7 is preferably secured 25 to the upper face of the carline and overlies the end thereof to provide a bearing upon the member 2. The gusset is secured to the member 2 by rivets 8 which are spaced a greater distance than the width of the ends of the carlines. The carline, gusset 7 and flange 6 are then secured together by rivets or other fastening members passed through the openings 9 which coincide with the openings already in the carlines and originally used to secure the carlines to the original 30 wood side plate.

In securing the repair construction to the original underframe, a rolled structural Z-member 3 is preferably used. The web of the Z is preferably horizontal and the inner downwardly directed 45 flange is secured to the underframe side sill. The advantages of so disposing the Z are many. A solid connection is obtained with the underframe, the web of the Z provides a support for the side posts, and the web of the Z can be placed in the 50 lower plane of the car floor so as to form a support therefor. Another extremely valuable result of this construction lies in the upwardly disposed outer flange 10 of the Z bar. The vertical depth of the flange provides a solid connecting means 55

for tying together the side post and side sheathing. In addition the thickness of the flange provides a greater section of metal at the floor line than is provided by the sheathing so as to retard failure from rusting at this point with the subsequent weakening of the side construction.

The side posts 4 are preferably formed of structural Z-bars or channels and are secured between the webs of the members 2 and 3 with the outer flanges of the posts overlapped by and secured to the outer flanges of the members 2 and 3. The side posts 4 are spaced longitudinally of the car and at the side door openings are displaced by the usual door posts 11. These posts may be of any suitable form and are secured to the members 2 and 3 in a manner similar to that used for the side posts 4.

The metallic sheathing 5 is preferably applied in panels extending in one piece between the members 2 and 3 and of a width sufficient to span the space between at least two adjacent posts 4. This sheathing is then secured to the posts 4 and members 2 and 3.

The usual door stops, track and guides are then secured to the members 2, 3, 4 and 10. End side ladders may be secured to the side construction by members secured to the members 2 and 3.

Steel sheathed cars are usually equipped with an inside lining of wood. To provide for this lining clip angles 13 are secured to the panels 5 as shown on Fig. 1. Nailing posts may then be secured to these angles 13 as shown in dot and dash lines on Figs. 1 and 2. The wood lining can then be nailed to said nailing posts and bear against the inner flanges of the side posts 4. It is to be understood that the door posts 11 will have the usual wood filler to which inside lining can be attached.

From the above it will be observed a complete side construction is formed which can be assembled upon the car as a unit. If desired the top and bottom members 2 and 3 may be spliced at the door opening and the construction assembled in two pieces. The preferred method of applying the repair side construction to a car is as follows: the car is prepared by removing the old wood side construction, the outside metal roof sheets and the entire roof structure. The repair side construction, having been previously assembled, is erected as a unit upon the car and the member 3 secured to the side sill. The roof carlines are prepared by attaching thereto the gusset plate 7 after which the gusset 7 and roof carlines are secured to the member 2. The ends of the side can then be secured to the car ends and the roof reapplied. In some cases where the original roofs comprised boards covered with metal roof sheets a wood nailing stringer 12 may be secured to the member 2 and the roof boards secured thereto.

All cars were not equipped with channel side sills as shown in Fig. 1, some being provided with Z-bar sills having an angle reinforcement on the inner flange. Two modifications of our invention showing its adaptability to various designs of underframe side sills are shown in Figs. 4 and 5.

In Fig. 4 the existing sill comprises a Z-bar with the web horizontal and an angle secured to the inner upwardly directed flange. For this type of car the lower Z-shaped member 3 of the repair construction is supplanted by an angle 14. The horizontal leg of the angle is secured to the web of the Z-bar sill member and the upwardly disposed vertical leg of the member 14 is secured to the post 4 and sheathing 5. The vertical leg of

the angle supplies all the advantages and functions of the vertical flange of the Z-shaped member 3 and by making the leg of sufficient length a double line of rivets can be used to secure the post to the angle. By so securing the post to the angle it is not necessary to bring the end of the post down upon the horizontal leg of the angle to secure a rigid connection.

In Fig. 5 is shown another method of attaching the repair construction to a car having an underframe similar to that shown in Fig. 4. Here a method similar to that shown and described in connection with Fig. 3 is used. The Z-bar bottom member 3 is secured to the sill Z-bar and angle as shown. This construction leaves an opening between the webs of the side construction and sill Z-bars which may be left open or filled with a wood stringer. However, it is undesirable to bring the sheathing 5 down to the flange of the side sill as the sheathing being thin would soon rust out at a point adjacent the top plane of the web of the sill Z-bar.

In Fig. 5 there is also shown a modification in the manner of securing the repair construction to the car roof. In some cases it may be desirable to retain the wood side plate of the car on account of roof conditions in which case the upper member of the side instead of being a Z-bar can be an angle with a down turned leg. When an angle is used the wood side plate is connected to the horizontal leg.

Having thus described the invention what we claim as new and desire to secure by Letters Patent is:

1. In a car repair construction, substituting metallic members for the original deteriorated wood sides of wooden box cars, the combination with the existing underframe and roof, of metallic side plates secured to and spanning a plurality of the roof carlines, metallic members extending longitudinally of and secured to each side sill, each of said side plates and members secured to the side sills having substantially vertical flanges spaced outwardly from the planes of the said existing car underframe and roof, said flanges on each side of the car being oppositely disposed, vertical posts at each side of the car, spaced longitudinally thereof and secured to said flanges and metallic sheathing secured to said posts, side plates and side sill members.

2. In a car repair construction, substituting metallic members for the deteriorated original sides of wooden box cars, the combination with the original roof and underframe, of metallic side plates spanning the ends of the transverse roof carlines, metallic bearing members secured to the side plates and to the ends of each carline, a metallic member secured to each side sill, extending longitudinally thereof and having an outwardly extending section below the upper plane of the car floor, a plurality of vertical posts spaced longitudinally of each of the sides of the car between the side plate and side sill members, to form a unitary structure and metallic sheathing secured thereto outside said posts.

3. In a car side wall repair construction adapted to be assembled as a unit and erected upon a car, in combination, a top member having a vertically disposed flange, a bottom member provided with a portion to be secured to an existing car side sill and having a vertically disposed flange spaced outwardly of the existing side sill, a plurality of vertically disposed posts secured to the vertically disposed flange of the bottom member and vertically disposed flange of the top mem-

- ber, and metallic sheathing secured to said posts and to the respective vertically disposed flanges of said bottom and top members.
4. A house car including: a metal side sill; a metal side plate; a sheet metal end; metal side posts; sheet metal side wall sheathing; means for attaching the upper edge of the sheathing to said side plate; means for attaching the sheathing to said side posts; and means for attaching the lower edge of the sheathing to the side sill including a metal member of substantially Z-cross section, the inner flange of which extends vertically and is riveted to the sill, the web extends horizontally, and the outer flange extends vertically and to which the lower edge of the sheathing is secured.
5. In a side wall replacement construction for application to the original metal underframe, having a metal side sill, of an originally side wood sheathed box car, a horizontally extending top metal side plate having an outer depending flange therealong, a horizontally extending lower metal member of Z cross section having its outer flange extending vertically and its inner vertical flange adapted to be secured to said side sill and dispose its said outer vertical flange in a plane spaced outwardly from a vertical plane passing through the outermost portion of said side sill, side wall metal posts including door and intermediate posts, metal sheathing constituting a complete closure from door post to car corner and between said side plate and bottom member, said sheathing being disposed on the outer sides of and secured to said intermediate posts and along its top and bottom edges to said side plate flange and outer flange of said Z member.
6. In a repair construction as used in converting wood sided box cars to steel sheathed box cars, the combination with the existing car side sill, of a metallic side plate, a metallic member disposed longitudinally of the side sill and secured thereto, flanges on said side plate and side sill member, said flanges being disposed in lateral spaced relation to said side sill, metallic posts connecting said side sill member and side plate, and sheathing extending between the side sill member and side plate and connected to said posts and to said laterally spaced flanges.
7. A box car including a metal side sill, a metal side plate, a metal end, metal side posts including a door post, sheet metal side wall sheathing, means for attaching the upper edge of the sheathing to said side plate, means securing the sheathing to said posts, and means connecting the lower edge of the sheathing to the side sill including a metal member of substantially Z-cross section extending between the door post and corner of the car, the bottom ends of the posts being anchored to said member, said member having its inner flange extended downwardly and riveted to the sill, its web extending horizontally and its outer flange extending upwardly and riveted to the sheathing.
8. A box car comprising an underframe including a metal side sill, a metal side plate, posts, sheet metal sheathing disposed in a vertical plane spaced laterally outwardly of the plane of the side sill, means rigidly securing the upper edge of the sheathing to the side plate, means rigidly securing the sheathing to the posts, and metallic means rigidly secured to and along the bottom edge of the sheathing, said means having a horizontal section and a vertical flange, the latter being riveted to the sill.
9. A box car comprising an underframe including a channel side sill, a side plate of angular cross section, posts of angular cross section, sheet metal sheathing disposed in a vertical plane laterally outwardly of the plane of the side sill and secured to said side plate and posts, and means, including a member of substantially Z-cross section with its web disposed horizontally, extending between and connected to the lower edge of the sheathing and the channel sill.
10. A box car including a channel side sill with the flanges thereof extended inwardly, a flanged metal side plate, door and metal side posts anchored at their upper ends to said side plate, sheet metal sheathing secured to the outer sides of said posts and along its upper edge to a flange of the side plate, said sheathing being disposed in a plane laterally outwardly of the web of the channel side sill, and metallic means of angular cross section secured to the bottom edge of the sheathing and extending from the plane of the latter inwardly to and secured to the web of the channel side sill, said means having a portion thereof so located as to provide a support for car flooring projecting outwardly beyond the side sill.
11. In a side wall replacement construction for application to the original metal underframe having a Z bar side sill, of an originally side wood sheathed box car, a horizontally extending top metal side plate having an outer depending flange therealong, a horizontally extending lower metal member having an outer flange extending vertically and a horizontal section and adapted to be secured to said Z bar side sill to dispose its said outer vertical flange in a plane outwardly of that portion of the side sill to which it is attached, metal posts including door and intermediate posts secured to the side plate and said lower member, metal sheathing constituting a complete wall closure from door post to car corner and between said plate and lower member, said sheathing being secured to the outer sides of said intermediate posts and along its top and bottom edges to said side plate flange and outer flange of said lower member.
